Primary Examiner — Clint A Samuel(74) *Attorney, Agent, or Firm* — Michael Best & Friedrich LLP**CLAIM**

The ornamental design for a lighting fixture as shown and described.

DESCRIPTION

FIG. 1 is a perspective view of a lighting fixture of the design;

FIG. 2 is a top view of the lighting fixture of FIG. 1;

FIG. 3 is a bottom view of the lighting fixture of FIG. 1;

FIG. 4 is a front view of the lighting fixture of FIG. 1;

FIG. 5 is a back view of the lighting fixture of FIG. 1;

FIG. 6 is a side view of the lighting fixture of FIG. 1; and

FIG. 7 is another side view of the lighting fixture of FIG. 1. The broken lines illustrate portions of the Light Fixture that

form no part of the claimed design.

1 Claim, 7 Drawing Sheets(56)
